United States Patent Office

Des. 215,980
Patented Nov. 11, 1969

215,980

BED PAN

Herbert A. Segal, Huntingdon Valley, Pa., assignor to
Samson Plastics, Inc., Cherry Hill, N.J., a corporation
of New Jersey

Filed May 15, 1968, Ser. No. 11,941

Term of patent 14 years

Int. Cl. D24—99; D28—01

U.S. Cl. D83—1

FIG. 1

FIG. 10

FIG. 2

FIG. 3

FIG.4

FIG.5

FIG.6

FIG.7

FIG.9

FIG.8

FIGURE 1 is a front perspective view showing my new design;

FIGURE 2 is a top plan view thereof;

FIGURE 3 is a bottom plan view thereof;

FIGURE 4 is a side view thereof;

FIGURE 5 is a front elevation view thereof;

FIGURE 6 is a rear elevation view thereof;

FIGURE 7 is a section view taken along line 7-7 of FIGURE 2;

FIGURE 8 is a section view taken along line 8-8 of FIGURE 2;

FIGURE 9 is a section view taken along line 9-9 of FIGURE 2; and

FIGURE 10 is a section view taken along line 10-10 of FIGURE 2.

The broken line representing the cap is shown for illustrative purposes only.

I claim:

The ornamental design for a bed pan, substantially as shown and described.
